Des. 215,874
Patented Nov. 4, 1969

215,874

VACUUM CLEANING DEVICE

Marnie C. Averitt, Timonium, Md., assignor to The Craftool Company, Woodbridge, N.J., a corporation of New York

Filed Oct. 18, 1968, Ser. No. 14,071

Term of patent 14 years

Int. Cl. D15—07

U.S. Cl. D49—13

FIG. 4.

FIG. 3.

FIG. 5.

FIG. 6.

FIGURE 1 is a perspective view of a vacuum cleaning device, showing my new design;

FIGURE 2 is a top plan view of the device illustrated in FIGURE 1;

FIGURE 3 is a side elevational view of said device;

FIGURE 4 is a front end view of said device;

FIGURE 5 is a rear end view of said device; and

FIGURE 6 is a bottom plan view of said device.

I claim:

The ornamental design for a vacuum cleaning device, as shown.
